GUN FOR SPRAYING POWDER

David L. Lott, Denver, Colo.

Application March 3, 1947, Serial No. 731,975

3 Claims. (Cl. 222—193)

1

This invention relates to improvements in devices for spraying powder.

It is frequently necessary to apply a dry powder to plants for the purpose of killing insects and it is also frequently necessary to spray a powder for the purpose of extinguishing fires.

It is the object of this invention to produce a dust gun or powder spraying device of a simple and substantial construction that can be employed as a fire extinguisher for use with fire extinguishing powders or as a dust gun for applying insecticides to plants or for any other similar purpose.

Although this device can be employed for specifically different purposes, it will be described in connection with the spraying of a fire extinguishing powder, it being understood, of course, that this is merely for the purpose of explanation.

There is available on the market today, a powder that is very effective for extinguishing fires if properly applied. In order to apply such a powder to a fire, it is necessary to employ a dust gun of sufficient force and capacity to direct a stream of the powder onto fire and to deliver a sufficient quantity thereof to effect the extinguishment.

It is the object of this invention to produce a dust gun of a size that can be readily operated manually, and which shall be provided with a double acting air pump for delivering the requisite amount of air under pressure to effect the powder distribution.

Another object of the invention is to produce a dust gun of the type indicated which shall be of such construction that it can be operated in a vertical direction either for the purpose of directing powder upwardly, or downwardly, and which can also be used in any intermediate angular position.

A further object of the invention is to produce a dust gun of such construction that it will not readily clog.

A still further object is to produce a dust gun having means for adjusting the parts so as to change the rate of powder discharge.

The above and other objects of the invention that may become apparent as the description proceeds are attained by means of a construction and an arrangement of parts that will now be described in detail and for this purpose reference will be had to the accompanying drawing in which the invention has been illustrated in its preferred form, and in which:

Figure 1 is a side elevation of the device;

2

Figure 2 is a top plan view of the device shown in Figure 1, the housing being shown in section to expose the interior parts.

Figure 3 is a section taken on line 3—3, Figure 2;

Figure 4 is a section taken on line 4—4, Figure 2; and

Figure 5 is an end elevation.

In the drawing reference numeral 10 designates a transparent cylinder, of some suitable plastic, which forms the housing for the mechanism that will now be described. Positioned within the housing is an air pump having a cylinder 11 made of some suitable metal. One end of the air pump cylinder is closed by means of a cap 12 and the other end by means of an end wall 13. Mounted for reciprocation within the cylinder 11 is a piston 14 that has been shown as of the double leather cup type suitable for compressing air in either direction. A tube 15 is positioned adjacent the outer surface of cylinder 11 and is connected with the interior thereof by a short tube 16, the other end of tube 15 is connected with the end wall 13 and its interior is in communication with the manifold 17. End wall 13 has an opening 18 that communicates the interior of cylinder 11 with the manifold 17. A double flat valve 19 is secured to the outer surface of end wall 13 in such a position that it can close either opening 18 or the opening into pipe 15. A piston rod 20 is connected with the piston and extends outwardly through cap 12 and terminates in a handle 21. The opening in cap 12 through which the piston rod extends, is, of course, provided with the usual packing so as to prevent air leaks at this point. At each end of cylinder 11 there is an opening 22 that is normally closed against the escape of air from the inside by means of a flat valve 23. It is now apparent that if the piston is moved in either direction, the air from that part of the cylinder whose volume is decreasing will be discharged into the manifold 17, either by way of pipe 15 or through opening 18 and at the same time air will enter the cylinder through opening 22 that is in communication with the part of the pump whose volume is increasing. We therefore have a double acting air pump discharging air into manifold 17 whenever it is operated.

Although a specific type of air pump has been shown and described, it is to be understood that any other construction can be employed. Since the air pump is merely there for the purpose of supplying air under some pressure, it is immaterial so far as the operation of the dust dis-

charging part is concerned, whether or not this compressed air is obtained from a pump or from a container having air under pressure.

Wall 13 serves in the present embodiment as a partition between the pump and that part of the mechanism that functions to discharge the powder.

Referring now more particularly to Figures 3 and 4, it will be observed that a tube 24 is connected with the manifold 17 and that another tube 25 is also connected with the manifold 17 by a somewhat S-shaped bend 26. Tubes 24 and 25 are jointed together at point 27, as shown in Figure 4 and therefore air or other material passing through the tubes will combine and be discharged through the outer end of tube 25, which projects beyond the point 27. A removable cap 28 serves to close the outer end of the housing 10 and is held in place by means of two rods 29 and 30 that are connected at one end with cap 12 and after passing through cap 28 are provided with wing nuts 31, which serve to urge the cap 28 into airtight sealing engagement with the end of the housing. If desired, a suitable gasket may be provided between the inner surface of cap 28 and the end of the cylinder 10, but since such gaskets are common for this purpose, it has not been illustrated.

Referring now to Figure 3, it will be observed that the passage from manifold 17 branches, one branch communicating with pipe 24 and the other with pipe 25. At the point where these two branches begin, a valve 32 is provided and mounted for rocking movement about pivot 33. One position of valve 32 has been indicated by full lines and another position by dotted lines. When valve 32 is in the full line position shown in Figure 3, any air leaving manifold 17 will be directed downwardly through the connector 26 and thence outwardly through tube 25. The latter is provided with an opening 34 adjacent which is located a screen 35. The pivot on which valve 32 turns extends through the wall of tube 24 and into a sealed chamber 36 whose wall has been designated by reference numeral 37. Secured to the end of pivot 33 that terminates in chamber 36 is an arm 38 to the end of which is secured a weight 39. In the finished device, compartment 36 is entirely closed so that no dust or air from the outside can enter the same. It will be apparent that if the dust gun is held in such a way that the end towards the left in the drawing is upwardly inclined, the action of weight 39 will move valve member 32 into the full line position shown in Figure 3 and therefore direct the current of air through pipe 25, whereas, if the dust gun is held in such a position that the end to the left is downwardly inclined, weight 39 will move into the dotted line position shown in Figure 4 and this, in turn, will move valve 32 into the dotted line position, thereby closing the passage to tube 25 and opening the passage to tube 24.

A partition 40 is provided to the right of manifold 17 as shown in Figure 3 and this forms a wall that prevents any powder from getting into that space between the manifold and partition 40. Opening 34 is positioned to the left of partition 40 as shown most clearly in Figure 4. Cap 28 may be removed entirely from the housing for the purpose of charging the chamber with powder or it may be provided with an opening having a removable cover 41. A short tubular discharge nozzle 42 is positioned in an opening in cap 28 in axial alignment with tube 25 and is adjust-

able inwardly and outwardly for the purpose of adjusting the rate of discharge, of the powder.

Let us now assume that the parts are assembled in the manner above described and that the compartment between cap 28 and partition 40 is partially filled with a fine powder. The powder containing compartment has been designated by P so as to be more readily referred to. If the fire or other object to which the powder is to be applied is positioned at a low elevation, the gun is pointed downwardly, whereupon weight 39 and arm 38 operate to move valve 32 from the full line to the dotted line position. The air will then pass through tube 24 and into tube 25 at point 27. Since the gun is pointed downwardly, the powder will naturally be resting against the inner surface of cap 28 and the stream of air emerging from tube 25 and escaping through tube 42 will entrain powder which will emerge in a stream and can be directed to whatever object may be desired. If the gun is used for applying an insecticide to plants, the stream of powder will naturally be directed onto the plant and if fire extinguishing powder is used, the stream of powder will be directed onto the fire. If, for any reason, the object to which the powder is to be applied is at an elevated position, the operator will naturally point the gun upwardly, whereupon weight 39 and arm 38 will move valve 32 to full line position shown in Figure 3. Any air that is now discharged from the pump or other source of air under pressure will pass through the part 26 through the screen and past opening 34, being discharged finally through the outer end of tube 25. Since the powder is resting against the outer surface of partition 40 when the gun is pointed upwardly, some of the powder will enter tube 25 through opening 34 and will be carried along by the stream of air and finally discharged from the gun, together with the air stream in which it is entrained. A screen 35 is positioned to the right of opening 34 for the purpose of preventing powder from entering the connecting passage 26 when the gun is not in use.

In Figure 3 the flat valves 23 have been shown as positioned inside of the cylinder where they would be likely to be interfered with by the cup leathers. In order to prevent such injury, the piston rod has been provided with a shoulder 43 and a projection 44 that serve as stops preventing the piston from engaging the valves. Any other suitable arrangement may, of course, be used and other equivalent valves may be substituted for the ones shown.

From the above description, it will be apparent that the dust gun that forms the subject of this invention is of such a construction that it can be used either for directing powder upwardly or downwardly and that the construction is such that the tubes can not readily become clogged during operation, or during the time when the gun is being transported.

Wall 13 serves the double function of an end closure for the pump cylinder and an end wall for the dust compartment P. In the embodiment illustrated, wall 40 forms an end wall of the dust chamber, its presence, however, is due to the fact that in its absence a greater quantity of powder would be necessary when the gun is operated in an upwardly directed position. Wall 40 may, however, be dispensed with and opening 34 brought closer to partition 13 which can be effected by obvious changes.

Having described the invention what is claimed as new is:

1. A dust gun comprising, an elongated housing closed at both ends, an air manifold near one end, a branched discharge opening in the wall of the manifold, a tube extending from one of the branches to a point near the other end of the housing, the wall of the housing having a discharge nozzle in substantial axial alignment with the open end of the tube, a second tube communicating the other branch of the discharge opening with the first mentioned tube at a point adjacent the discharge end of the latter, a valve means positioned in the discharge opening for directing air from the manifold to either tube, a gravity responsive means for positioning the valve to direct an air stream into the first mentioned tube when it is upwardly inclined and into the second mentioned tube when the parts are downwardly inclined, the first mentioned tube having its wall provided with an opening adjacent the valve, and means for supplying the manifold with air under pressure.

2. A dust gun comprising an elongated housing forming a dust compartment, walls closing the ends of the housing, an air manifold adjacent one end wall, the inner wall of the manifold having a branched opening, a tube having one end in communication with one of said branches, the other end terminating a short distance from the inside of the other end wall, a tubular discharge nozzle extending through the end wall, terminating adjacent to and in substantial axial alignment with the open end of the tube, a second tube communicating the other branch of the manifold opening with the first mentioned tube, the first mentioned tube having an opening in its wall adjacent the end in communication with the manifold opening branch, means for supplying

the manifold with air under pressure, means for directing air from the manifold into the first mentioned tube when the gun is upwardly inclined and into the second tube when it is downwardly inclined, said means comprising a valve member in the branched opening, and means comprising a gravity responsive operating device for moving the valve member in response to the angular position of the gun.

- 10 3. A dust gun comprising, an elongated housing whose ends are closed by transverse inner and outer walls, the inner wall being transversely inclined, a closed manifold chamber positioned outside of the inclined end wall, the wall of the manifold adjacent the inclined wall having a branched discharge opening, means for supplying air under pressure to the manifold, a tube having its inner end in communication with one of the branches through an S-shaped connector, the other end of the tube terminating adjacent the inner surface of the outer wall, a tubular nozzle extending through the outer wall in axial alignment with the tube, the wall of the tube having an opening positioned adjacent the inside of the inner end wall, and a gravity responsive valve mechanism for directing air into the first mentioned tube when the gun is upwardly inclined and into the other tube when the gun is downwardly inclined.
